UNITED STATES PATENT OFFICE.

AMBROSE SWASEY, OF CLEVELAND, OHIO, ASSIGNOR TO THE WARNER & SWASEY COMPANY, OF CLEVELAND, OHIO, A CORPORATION OF OHIO.

TELESCOPIC SIGHT FOR FIREARMS.

No. 820,998.

Specification of Letters Patent.

Patented May 22, 1906.

Application filed October 10, 1905. Serial No. 282,098.

To all whom it may concern:

Be it known that I, AMBROSE SWASEY, a citizen of the United States, residing in Cleveland, in the county of Cuyahoga and State of Ohio, have invented certain new and useful Improvements in Telescopic Sights for Firearms, of which the following is a specification.

This invention relates to sight devices used to obtain an accurate aim in shooting, and is particularly adapted for firearms, such as rifles.

One of the objects of the invention is to produce a gun-sight of minimum size and weight and one which can be readily removed from the firearm and conveniently carried by the rifleman.

Another object of the invention is to provide improved means for adjusting the inclination of the gun-sight and also means for securing the gun-sight when so adjusted.

A further object is to provide means for adjusting the sight device longitudinally along the firearm and means for adjusting the inclination in such positions.

In the accompanying drawings, illustrating a gun-sight embodying my invention, Figure 1 shows in side elevation the middle portion of a rifle with the gun-sight mounted thereon. Fig. 2 is a vertical section through the adjusting-screw of the movable sight, showing also its threaded socket. Fig. 3 shows in plan the indicating-sleeve of the screw. Fig. 4 is an end view of the latter. Fig. 5 is a rear elevation of the gun-sight with the eyepiece removed. Fig. 6 is a view on the line 6-6 of Fig. 5. Fig. 7 is a bottom plan view of the bar supporting the sight device, partly shown in section. Fig. 8 is a vertical transverse section on the line 8-8 of Fig. 1. Fig. 9 is an enlarged horizontal section on the line 9-9 indicated in Fig. 5, partly shown in elevation. Fig. 10 shows in plan the locking-spring shown in Fig. 9. Fig. 11 shows the plate for the locking-spring. Fig. 12 shows the adjusting means for the vertical cross-wire. Fig. 13 shows the traveling nut connected with the cross-wire. Fig. 14 is a vertical section taken through the axes of the sight device. Fig. 15 is a transverse section through the sight device on the line 15-15 indicated in Fig. 14. Fig. 16 is an enlarged transverse section on line 16-16 indicated in

Fig. 14, and Fig. 17 shows the adjustment of the eyepiece-lens.

The invention consists, essentially, of two members, a supporting member that is removably secured to the firearm and a sight device that is adjustably mounted on the supporting member. The supporting member is arranged to be removably attached to the firearm and secured thereto, preferably, in adjusted positions. In the present instance the supporting member comprises a bar 12, having a straight portion 13, provided with a dovetailed slot 14. A suitable strip 15 is provided with a portion arranged to slidably engage the dovetailed slot, which strip is secured to the firearm 16, preferably along one side. The supporting-bar can be readily attached to the firearm by sliding it on this strip and may be located in several longitudinal positions by suitable means. In Figs. 1 and 8 the bar is shown as provided with a spring-pin 17, having an arm 18, which is caused to enter suitable notches 19 in the strip 15 when the bar is moved to such positions.

To the rear portion of the bar is suitably pivoted the sight device, (denoted generally by 20.) The sight device is preferably pivotally mounted on its forward portion at an intermediate portion of the bar 12 by a pivot-pin 21 passing through extensions of the frame of the sight device and projecting portions of the bar. Suitable adjusting means is provided between the rear portion of the sight device and the rear portion of the supporting-bar, whereby the sight device can be rocked on the pivot and also secured in adjusted positions. At the rear end of the bar 12 is provided a socket portion 22, having a vertical bore that is threaded to engage with a screw 23 mounted therein. The upper end of the screw has a reduced shank with the extremity slightly rounded and also has a collar 24 on this shank a short distance from the end. The end of the screw-shank engages the bottom of the sight device, and the movement of the screw up or down will raise or lower the sight device—that is, rock it on its pivotal support. To maintain the engagement of the screw with the sight device, a member is provided on the bottom thereof. This member (shown separately in Fig. 6) comprises a base portion 25, secured

to the bottom of the frame of the sight device in any suitable manner, such as by screws. The base 25 has an arm 26 extending downward and then rearward, that has its rear portion forked at 27 to engage the screw-collar 24 and a sleeve portion 28 of the screw. The inner face of the arm 26 is rounded where it engages the collar 24. By this means the advancement of the screw upon rotation will carry the sight device up or down, according to the direction of rotation. The rounded end of the screw-shank and also the rounded engaging portion of the arm 26 with the collar will permit of the swinging movement of the sight device on its pivotal support on the bar 12.

The screw 23 carries a suitable indicating device for showing the amount of adjustment of the sight device. An annular scale 20 is arranged on the socket 22, and a sleeve 29 is suitably secured to the screw to rotate therewith, which sleeve has an annular scale extending to its tapered extremity and at that place registering with the annular scale 25 on the socket. The lower end of the screw 23 has a reduced shank 30, made somewhat square or polygonal to engage a similar aperture in a head 31, which head is secured to the screw-shank by means of a nut 32 engaging the threaded end portion of the screw-shank 30. The sleeve 29 is secured to the head 31 by means of an internal flange 33 on the sleeve being engaged by a ring 34, that is clamped to the head 31 by means of screws 35 passing through the head and tapped into the ring 34.

Suitable means are provided for securing the sight device in the positions to which adjusted by the screw 23. In the present instance the collar 28 of the screw is provided with longitudinal ribs. The supporting-bar at the rear end is provided with a bore 36, one part of which communicates with the bore for the screw 23. In this bore is mounted a bolt 37, having a head 38 lying in the portion of the bore communicating with the other bore, and a nut 39 on the bolt 37 serves to draw the head 38 into engagement with the collar 28 of the screw, which will serve to prevent rotation of the screw 23. A spring 40 serves to retract the head 38 of the screw when the nut is loosened, causing the head to disengage the collar 28.

The sight device is shown as used with 55 Porro prisms, which deflect the line of sight four times and considerably shorten the distance of the line of sight. The Porro prisms are rigidly secured to a single member, that may be removed from the sight device when 60 desired. Between the prisms and the eyepiece are arranged cross-wires for properly focusing on the desired object. The horizontal cross-wire is carried or etched on one face of a disk or reticule 42, mounted in the 65 lens-tube 43. The vertical cross-wire is

etched on one face of a glass plate 44, that is supported to be horizontally adjustable in order to provide for drift or lateral deflection of the sight. The plate 44 is secured in a frame 45, fast to or a part of a traveling nut 70 46. The plate 44 is supported to slide horizontally in a guide member 47. A screw 48 engages the traveling nut 46 and is rotatably supported in a part 49 of the frame, but prevented from advancing therein by means of a collar 50 on the screw engaging the inner face of the part 49 and a suitable head 51, secured to the outer end of the screw. The head 51 has a collar 52 secured near its periphery and extending inward near the frame 80 member. Inside of this collar is located a retaining means comprising a curved spring-plate 53, secured to the head at one end and having its other end bent downward and engaging a notched plate 54, fast on the frame 85 member. By suitable force being applied to the head 51 the screw will be rotated and the nut advanced in either direction as desired; but the end of the spring-plate will engage the notched plate and serve to retain the 90 screw in the adjusted position. A coil-spring 55 is provided between the nut and the frame to prevent any movement of the nut from backlash.

In Fig. 17 is shown a plan of the adjustment of the eyepiece-lens, the outer tube being in section. One of the lens-tubes 60 slides in another lens-tube 61, and the latter has a diagonal slit 62, into which extends a lug 63 to cause a screw-threaded engagement 100 of these tubes, whereby they are adjusted. An outer tube 64, secured to the inner tube 60, carries a spring-latch 65, whose end is ridged to engage a ribbed ring 66 and secure the tubes in adjusted position, as shown in 105 Fig. 16.

What I claim is—

1. The combination of a supporting member arranged to be secured to a firearm, a sight device pivotally mounted on the supporting member, a socket portion on the supporting member having a screw-threaded bore, a screw operating in said bore and engaging the sight device by one extremity, the screw having an annular slot adjacent said end, and an arm secured to the sight device and engaging the screw at said slotted portion.

2. The combination of a supporting member arranged to be secured to a firearm, a sight device pivotally mounted on the supporting member, a socket portion on the supporting member having a screw-threaded bore, a screw operating in said bore and engaging the sight device by one extremity, the screw having an annular slot adjacent said end, an arm secured to the sight device and engaging the screw at said slotted portion, a collar on said screw, the supporting member having a bore extending transverse to said 125 130 135

bore and having an enlarged portion communicating therewith, a bolt located in said latter bore with its head in said enlarged portion, and a nut on said bolt arranged to move it and cause its head to engage said collar on the screw and lock the latter against movement.

3. The combination with a firearm, of a bar removably attached thereto, pivoting members extending upward at an intermediate part of the bar, a sight device having pivoting members at its lower forward portion engaging said pivoting members, whereby the sight device is pivoted on the bar, the supporting member being provided with an upright screw-threaded bore in its rear portion, a screw operating in said bore and provided with a collar adjacent its upper end, a bearing member secured to the bottom of the sight device at its rear end arranged to engage the end of said screw, the bearing member being provided with a forked arm engaging said screw below its collar, whereby the rotation of the screw will swing the sight device on its support, and a clamping-bolt arranged to lock the screw against rotation.

4. In a sight device, the combination with the lenses, of a cross-wire member movable across the axis of the lenses, a frame supporting the cross-wire member, a guide in which said frame is slidable to move the cross-wire member, a nut secured to said member, a screw engaging said nut to adjust the cross-wire member, and a spring-latch for locking the screw in adjusted positions.

5. In a sight device, the combination with the lenses, of a cross-wire member movable across the axis of the lenses, a frame supporting the cross-wire member, a guide in which said frame is slidable to move the cross-wire member, a nut secured to said member, a

screw engaging said nut to adjust the cross-wire member, and a coil-spring on the screw for preventing backlash between the screw and nut.

6. In a sight device, the combination with the lenses, of a cross-wire member movable across the axis of the lenses, a frame supporting the cross-wire member, a guide in which said frame is slidable to move the cross-wire member, a nut secured to said member, a screw engaging said nut to adjust the cross-wire member, a latch-plate carried by the device, and a spring-latch secured to the head of the screw and engaging the latch-plate to lock the screw in adjusted positions.

7. The combination, in a sight device, of a body member having a tubular portion and carrying a lens disposed in the axis of said portion, a tubular eyepiece telescoping said tubular portion and having a screw-threaded engagement therewith, a spring-latch carried by one of said tubular members, and an annular latch-plate engaged by said latch to lock said members in adjusted positions.

8. The combination of a supporting member organized to be secured to a firearm, a sight device pivotally mounted on the supporting member, the supporting member having a cylindrical portion provided with a screw-threaded bore, a screw operating in said bore and connected with the supported member for adjusting the same on its pivotal support, and a cam member, having a tangential engagement with the shank of the screw for locking the same in adjusted positions.

AMBROSE SWASEY.
